UNITED STATES PATENT OFFICE

160,846

CANISTER UNIT

Lillian George Edmonson, Columbus, Miss.

Application January 23, 1950, Serial No. 7,405

Term of patent 14 years

(Cl. D44—6)

To all whom it may concern:

Be it known that I, Lillian George Edmonson, a citizen of the United States, residing at Columbus, in the county of Lowndes and State of Mississippi, have invented a new, original, and ornamental Design for Canister Unit, of which the following is a specification, reference being had to the accompanying drawing, forming part thereof.

Fig. 1 is a perspective view of a canister unit, showing my new design with the cover and lower sections open; and

Fig. 2 is a front elevational view thereof.

I claim:

The ornamental design for a canister unit, as shown.

LILLIAN GEORGE EDMONSON.
